WELL TREATING APPARATUS

Earl D. Ayers, Auburn, Mich.

Application April 4, 1956, Serial No. 575,992

6 Claims. (Cl. 102—20)

This invention relates to a method of and apparatus for selectively operating through the same electrical conductors of a supporting cable two electrically operated bore hole logging or treating devices.

Oil or gas wells are often completed by running casing to the bottom of the bore hole and then forcing cement through the casing and into the space between the well bore wall and the casing. Cementing the casing in place in the well bore effectively prevents fluids emanating from one or more strata along the well bore from contaminating other strata. However, the cementing operation usually seals off the oil producing strata as well as those strata which are capable of producing undesired fluids or which are capable of absorbing fluids.

Customarily the casing and cement are perforated adjacent to the oil producing strata in order to permit oil from the producing strata to enter the casing. Perforation of the casing and well bore wall (including cement) is usually accomplished by suspending a perforating gun from a suitable electric cable and lowering the gun into the well bore until the gun is beside the producing formation, and then firing the gun.

Although the depth below the earth's surface of the producing formation is usually known from data taken as the well is drilled, it is not customary to rely on such data in determining where the casing is to be perforated. Usually a radioactivity log is made of the formations adjacent to the well bore and the perforating gun is disposed, for firing, at a depth indicated by the well survey of the radioactivity of the formations. This has, in the past, been somewhat time consuming in that the well bore logging device is first lowered into the well bore to make the log of radioactivity of the adjacent formations and then must be removed from the well bore before the perforating gun is lowered into the well bore. Usually the well bore logging device and the perforating gun are lowered on the same cable (although at different times) in order to avoid possible errors in depth measurement which might occur if two different cables were used.

Accordingly, a principal object of this invention is to provide an improved apparatus and method for selectively operating a well bore surveying device and a well bore perforating gun from the same electrical conductors of a cable containing at least two electrical conductors, one of which is insulated.

In accordance with this invention there is provided a gas filled radiation detector of the Geiger-Muller tube type and a well bore perforating device electrically connected in series. The perforating device and the radiation detector, electrically connected in series, are suspended from a cable having at least one conductor which is insulated from the well bore fluids. The radiation detector and the perforating device are disposed side by side as they are lowered into the well bore. The radiation detector has an anode which is connected directly to the insulated conductor and a cathode which is connected to a detonating means requiring a relative heavy current (as

2

compared to the detector current) to fire it. The detonating means is connected to a ground return conductor. When the desired radiation pattern is received and identified through radiation counting apparatus located at the surface, the potential on the cable is increased sufficiently to break down the radiation detector and fire the perforating device. Both the radiation detector and the perforating device are made of frangible material which is broken into small pieces by the explosion of the perforating device.

The invention, as well as additional objects and advantages thereof, will best be understood when the following detailed description is read in connection with the accompanying drawing, in which:

15 Fig. 1 shows, in diagrammatical form, the apparatus of this invention.

Referring to the drawing, there is shown a well bore, indicated generally by the numeral 10, extending from the surface 12 of the earth through various strata or earth formations 14, 14a, 14b. The well bore contains a string of casing 16 which extends from the earth's surface 12 to near the bottom 18 of the well bore 10. The space between the casing 16 and the wall 20 of the well bore is filled with cement 21 from the bottom 18 of the well bore to the earth's surface 12, for example.

20 Disposed within the well bore 10 is a cable, indicated generally by the numeral 22, which includes an inner, insulated conductor 24 and a grounded conductor 26 which is commonly, but not necessarily, the metal sheathing or load carrying part of the cable 22.

25 Above the surface 12, the cable 22 passes over a sheave 27 supported by a derrick 28 and is coiled onto a reel 30. The inner conductor 24 is connected to a commutator element 32 on the reel 30 and electrical connection 35 to the insulated conductor 24 of the cable 22 is made through a brush contact member 34. As illustrated in the drawing it is assumed that the outer conductor 26 is the metal, load carrying outer part of the cable 22 and that the conductor 26 is grounded, as indicated by the ground connections 36, 38 at any convenient point, as 30 through the reel 30 and derrick 28 to the earth 12, for example.

30 A perforating gun, indicated generally by the numeral 40, and a radiation detector, a Geiger-Muller tube, indicated generally by the numeral 42, are attached at the lower end 44 of the cable 22. The gun 40 and tube 42 are, in practice, physically disposed side by side. The anode 46 of the tube 42 is electrically connected to the inner or insulated conductor 24 of the cable 22. The cathode 48 of the tube is electrically connected to the detonating means of the gun 40, commonly a blasting cap 50 requiring an ampere or more of current to detonate it. The blasting cap 50 also is electrically connected to the ground return conductor 26 by any convenient means 55 such as the ground connection 52.

35 A fuse 54 which is capable of carrying current of the order of a few milliamperes is connected in shunt across the detonating means 50. A condenser 56 is also connected in shunt across the detonating means 50. Although the detonating or firing means 50 for the perforating gun 40 may be a blasting cap, other current actuated devices such as a resistance heating element (not shown) adapted to ignite a powder charge upon the passage 40 through the element of a specified current may be used in firing the gun 40.

45 A power source, indicated generally by the numeral 60, is illustrated as two batteries 62, 64 connected in series with the cathode of the battery 64 grounded, as at 66. The lead 68 connects the two batteries 62, 64 to a terminal of a multiple terminal switch 70. The lead 72 connects the anode of the battery 62 to another terminal

of the switch 70. The switch 70 is coupled through a series resistor 74 and lead 76 to the commutator brush 34. A switch 78 is connected in parallel with the resistor 74 and permits the resistor 74 to be by-passed, for reasons which will be explained later.

A pulse count indicator 80, which may be energized by any suitable source of power (not shown) is connected to ground as indicated by the connection 82 and is coupled to the commutator bar 34 through the lead 84 and the condenser 86.

In operation the perforating gun 40 and radiation detector 42 are attached to the end 44 of the cable 22 with electrical connections between the conductor 24 and the gun 40 and detector 42 being made through suitably enclosed connectors (not shown) to prevent the inner conductor 24 of the cable 22 from being grounded directly and not through the desired loads (tube 42 and gun 40). The radiation detector 42, a Geiger-Muller tube, is energized by connecting the arm 88 of the switch 70 to the anode lead 68 of the battery 64. It will be assumed that the battery 64 provides a direct current potential, say 1000 volts, which is sufficient to energize and operate the tube 42 but is not sufficient to break down the tube and cause it to conduct heavily, thus firing the detonator means. The fuse 54, which will safely carry the current needed to operate the tube 42, shunts current around the detonating means 50 to the ground return conductor 26 through the ground connection 52.

With the radiation detector energized, the detector 42 and gun 40 are moved up and down the well bore 10 to determine the radioactivity of the adjacent earth formation. As gamma rays from the various formations strike the detector 42, pulses are transmitted up the cable 22 and are coupled through the lead 84 and condenser 86 to a pulse count indicator 80 of suitable design.

When the radioactivity survey indicates that the gun 40 and detector 42 are disposed beside the desired earth strata or formation 14a, the switch 78 is then closed to short out the resistor 74 which is a current limiting resistor. (With the current limiting resistor in the firing circuit, the current passing through the firing circuit with the detector tube 42 "broken down" and conducting, would be insufficient to detonate a firing means 50 such as a blasting cap which requires at least an ampere of current to detonate it.) The arm 88 of the switch 70 is then turned to the terminal connected to the lead 72 and the full potential (batteries 62, 64 connected in series) of the power source 60 is applied across the radiation detector 42 and across the detonating means 50, fuse 54, and condenser 56. The Geiger-Muller tube 42 breaks down and conducts heavily when the higher gun firing potential is applied across the tube 42, thus permitting a sufficient current to pass through the detonator means 50 to permit the firing of the gun 40.

When the full potential, say 2,000 volts, of the power source 60 is applied to the firing source, the tube 42 ionizes and breaks down, applying the full potential of the power source 60 across the detonating or firing means 50. Under such conditions sufficient current flows to blow the fuse 54, causing all the current to flow through the firing means 50, usually a blasting cap which fires when an ampere of current passes through it, to fire the perforating gun 40. The perforating gun 40 may be of the structural type shown in U.S. Patent No. 2,733,657 to C. M. Bryant et al., for example, which has incorporated therein detonating means of the blasting cap type requiring an ampere or more of current to detonate it. The charges of the gun, which usually are of the well known "shaped charge" type, perforate the casing and cement when fired, permitting fluid from the adjacent earth formations 14 to flow into the casing 16. The explosion attendant to the firing of the gun 40 normally shatters the gun 40 and the Geiger-Muller tube 50,

leaving no large sections of material to interfere with the later operation of the well.

The perforating gun 40 and Geiger-Muller tube 42 are described heretofore as being disposed side-by-side. The 5 Geiger-Muller tube 42, however, may be disposed either above or below the gun 40. Thus, in operation of the invention when the detector tube 42 is not beside the gun 40, the zone or strata to be "shot" is located by the detector tube 42 and the gun is then raised or lowered 10 a short distance to the indicated shooting position. An explosive charge, adapted to detonate when the gun 40 is fired, should be provided adjacent to the tube 42 to insure that no large pieces of the tube 42 remain to clog the bore hole after the gun 40 is fired.

15 Further, a rectified alternating current power source, suitably filtered, may be substituted for the batteries 62, 64 of the power source 60.

The Geiger-Muller tube may be made of glass tubing, 20 having a wire anode axially disposed therein and a cathode electrode disposed along the inner wall of the tube. The tube is filled with a suitable gas at a suitable pressure, as is well known in the art of making Geiger-Muller tubes, to permit the operation of the tube at a desired potential. The cathode of the tube may, for example, 25 be an aquadag coating on the inner wall of the glass tube. Other Geiger-Muller tubes may be used in accordance with this invention provided their electrode structures permit their breaking down and conducting sufficient current to fire the gun 40 at potentials within 30 the limitation of insulation of the cable 22.

The resistor 74, mentioned before, is inserted in series 35 with the lead 76 to the commutator brush 34 to prevent enough current being passed through the conductor 24 to fire the perforating gun 40 in event the full output of the power source 60 were accidentally applied to the conductor 24. The switch 78 permits the shorting out of the resistor 74 when it is desired to fire the gun 40.

The fuse 54 is not necessary for the operability of this 40 invention, but serves at least a psychological purpose in shunting current around the firing means 50 even though the current used in operating the tube 42 would be insufficient to detonate the firing means.

It is thus apparent that this invention provides a simple 45 means for locating a perforating gun 40 opposite a desired earth formation 14a as the gun 40 is lowered in a well bore 10. This invention eliminates the usual time consuming separate radioactivity survey run into the well bore 10 and permits survey and firing of the perforating gun to be done in one instrument run into the well bore.

50 I claim:

1. Apparatus for locating a desired earth formation which is penetrated by a well bore, for positioning an explodable perforating device adjacent to said desired earth formation and then detonating said perforating device, comprising, a cable having an insulated conductor and a ground return conductor therein, said cable having an upper end and a lower end; a circuit comprising 55 a Geiger-Muller tube comprising an anode electrode and a cathode electrode, and a current actuated firing means for said perforating device, said firing means including two electrical leads, said anode electrode being electrically connected to said insulated conductor, said cathode being electrically connected to one of the leads of said firing means, the other of said leads of said firing 60 means being electrically connected to said ground return conductor, a radiation pulse count indicator, means coupling said pulse count indicator to said insulated conductor of said cable, a power source having high and intermediate output potentials, and means for selectively applying said potentials between said insulated conductor and said ground return conductor.

65 2. Apparatus in accordance with claim 1, wherein said current actuated firing means is a blasting cap which is capable of being detonated on the passage therethrough 70 of current of the order of one ampere.

3. Apparatus in accordance with claim 1, wherein said current actuated firing means is an electrical resistance element.

4. Apparatus in accordance with claim 1, wherein a condenser is connected in parallel with said firing means.

5. Apparatus in accordance with claim 1, wherein a low-current fuse is connected in parallel with said firing means, said fuse being capable of passing only a minor fraction of the current necessary to detonate said firing means.

6. Apparatus in accordance with claim 1, wherein said means for selectively applying said potentials includes a

resistor connected in series with said power source and said insulated conductor and a switch for selectively shunting out said resistor.
